UNITED STATES PATENT OFFICE.

ROY R. QUACKENBUSH, OF COMSTOCK PARK, MICHIGAN.

BOTTLE.

Application filed August 18, 1926. Serial No. 130,009.

This invention relates to a bottle, one of the objects being to provide a device of this type which after once being filled cannot be readily refilled without detection although 5 the structure is such as to permit the contents to be easily poured therefrom.

With the foregoing and other objects in view which will appear as the description proceeds, the invention resides in the combination and arrangement of parts and in the details of construction, hereinafter described and claimed, it being understood that changes in the precise embodiment of the invention herein disclosed may be made within 15 in the scope of what is claimed, without departing from the spirit of the invention.

In the accompanying drawings the preferred form of the invention has been shown.

In said drawings, 20 Figure 1 is a vertical transverse section through the bottle.

Figure 2 is a section on line 2—2, Figure 1, the stopper being shown in elevation.

Figure 3 is a section on line 3—3, Figure 1. 25 Referring to the figures by characters of reference 1 designates the body of the bottle which can be of any desired contour and the neck 2 thereof is provided with separate openings 3 and 4 adapted to be closed by means of stoppers 5 and 6 respectively.

A tubular stem 7 formed of glass is integral with and opens through the bottom of the bottle while the upper end of this stem is pointed and closed as shown at 8 and projects into the opening 3. Obviously, therefore, when the stopper 5 is placed in position within the opening 3 it will engage and surround the pointed end portion of this stem. If desired a suitable adhesive may be placed in the recess 9 into which the stem projects so that after the stopper has been placed in closed position it will adhere to the stem and thus make it impossible to remove the stopper without breaking the stem 7. 40 Consequently any liquid thereafter placed in the bottle will escape through the stem provided the level thereof rises above the upper end of the broken stem. In any event, however, the breakage of the stem would serve 45 as a means for indicating that the original contents have been removed.

A partition 10 is formed within the bottle near the neck portion 2 but beneath the opening 4, this partition forming a pocket 11 having a drain opening 12 through the wall of 55 the bottle close to the bottom of the pocket. The upper end of the pocket communicates with the opening 4 and extends across the greater portion of said opening. The stopper 6, when placed in the opening 4, will rest 60 upon the upper end of the partition and serve not only to close the outlet from the bottle through the throat 13 which is provided between one wall of the bottle and the partition 10, but also serving to close the 65 upper end of the pocket 11.

When it is desired to fill the bottle the liquid is poured through the opening 3 after which the two stoppers 5 and 6 are placed in position, stopper 5 being affixed to the end of 70 stem 7 as before explained. Thereafter should it be desired to remove the contents it is merely necessary to remove stopper 6 whereupon liquid will flow outwardly 75 through the throat 13 and the opening 4. Should an attempt be made under ordinary conditions to fill the bottle through the opening 4, a large portion of the liquid would enter the pocket 11 and drain through the opening 12. This would of course result in 80 waste under some circumstances. Obviously any attempt made to fill the bottle by removing stopper 5 would result in breakage of the stem 7 as already explained.

What is claimed is:

A bottle including a body, a neck having separate openings, a pocket within the bottle extending partly across one of the openings to provide a relatively small outlet throat for maintaining communication between the interior of the body and one of the openings, there being a drain opening in the wall of the bottle adjacent the bottom of the pocket to prevent retention of liquid in the pocket, and a removable stopper for each of 90 of the openings, one of said stoppers constituting means for engaging the top of the pocket and closing the throat.

In testimony that I claim the foregoing as my own, I have hereto affixed my signature.

ROY R. QUACKENBUSH.
